TURBINE

Carl R. Waller, Trenton, N. J., assignor to De
Laval Steam Turbine Company, Trenton, N. J.,
a corporation of New Jersey

Application August 24, 1932. Serial No. 630,167

9 Claims. (Cl. 253—59)

This invention relates to a turbine and has particular reference to means whereby a turbine may be efficiently operated at different speeds, the change from one speed to another being effected by remote control.

In connection with equipment furnished for water gas plants, it is quite essential to be able to control the turbine driving the air compressor from the gas machine. When making gas the blower equipment is operated for a certain number of minutes until the gas machine is "charged," after which the blower equipment must be instantaneously shut down and kept at idling speed for a fixed number of minutes after which time it is again brought up to full speed. Heretofore this control of the blower equipment was generally obtained by opening and closing the steam valve, or valves, admitting steam to the turbine. To accomplish this, varying types of equipment have been used. The most common arrangement has been a hydraulic system that is so arranged that when certain valves on the gas machine are being operated the operator can also simultaneously, by means of a hydraulic valve, cause the flow of steam to the turbine to be changed. This particular system, however, is rather expensive as it entails a lot of piping and relatively elaborate control mechanism. One system of this general type is illustrated in my prior patent, 1,837,382, dated December 22, 1931.

It is also found that in this type of machinery it is quite important that the idling speed is maintained so that the machine can be brought to full speed without time lag. The exact amount of idling speed depends somewhat on the arrangement of the piping between the blower and the gas machine, the idling speed being always necessarily such as to prevent the gas from flowing back through the blower.

For the more efficient operation of a turbine, it is desirable that instead of operating the main set of nozzles under reduced flow of steam it is better to operate a single nozzle with a full flow of steam so that while the nozzle works at full efficiency a lower speed of operation of the rotor is attained.

The objects of the invention relate to the avoidance of difficulties and the attainment of the desirable results indicated above. Specific objects of the invention relating primarily to details of construction will be apparent from the following specification read in conjunction with the accompanying drawings in which:

Fig. 1 is an elevation partly in section showing various parts of the steam controlling elements of the turbine;

Fig. 2 is a plan view with certain parts broken away showing the improved devices; and

Fig. 3 is an elevation of the same partly in section.

The casing of the turbine is indicated at 2, this turbine, in the present instance, being of a conventional single stage type, although it will be obvious that the invention is applicable to other types of turbines. The rotor of the turbine is indicated at 4, this rotor carrying buckets 6 which receive steam from the main nozzles 8 one of which is shown. Steam is supplied to the nozzles 8 from the steam chest 10, the admission of steam to which is controlled by a valve 12 located between the steam chest and the supply passages 14. The valve 12 is carried by a spindle 16 and is normally urged outwardly by a spring 18 reacting between a portion of the frame and a collar carried by the outer end of the spindle. The depending arm of the bell crank 20 engages a collar 22 on the valve spindle 16, this bell crank being controlled through a vertical link 24 and a suitable lever by the upwardly projecting rod 26 of a conventional governor mechanism located within the housing 28, this governor mechanism being driven from the turbine shaft. If the speed of the turbine increases beyond a predetermined amount the plunger 26 rises causing the bell crank 20 to swing in a clockwise direction as viewed in Fig. 1 and move the valve 12 towards its closed position to throttle or completely cut off the entry of steam to the steam chest 10. The parts so far described are quite conventional in the control of a turbine of this character. A suitable blower is directly connected to the turbine shaft in cases when the turbine is used in water gas plants. A suitable hand valve which is not shown is provided in the main steam line to control the entry of steam to the passages 14 about the valve 12.

The nozzles 8 forming the main series will drive the turbine at its full speed, the nozzles being designed to operate efficiently when the proper flow for accomplishing this takes place. In addition to the main set of nozzles there is provided in the present instance an auxiliary nozzle 30 which is designed to drive the rotor at a suitable idling speed when the proper flow therethrough takes place. The nozzle 30 is not supplied with steam from the chest 10 but receives its supply through a pipe-line 32 which communicates with the passages 14 about the valve 12 as indicated at 34. It will be obvious from this that the flow of steam to the auxiliary nozzle is independent of the valve 12. In the line 32 there is located a valve 36 which may be of a plug type, the valve

element being operated through the medium of a lever 38 which has a suitable pin and slot connection with a lever 40 pivoted at 42 to the frame.

The short end of the lever 40 indicated at 44 5 engages a collar 46 carried by the valve spindle 16, the engagement being such that the lever 40 may move in such direction as to close the valve without, however, interfering with its independent closure under the action of the governor mechanism.

The opposite end of lever 40 indicated at 48 is bifurcated and engages within an opening in a block 50 which is slidable on a screw 52 journaled in the frame. A nut 51 suitably guided to 15 prevent its rotation is threaded on the screw 52 and there is interposed between this nut 51 and the block 50 a compression spring 53. The screw 52 is driven through suitable reduction gearing contained in the housing 54 by a motor 56, the 20 motor being of reversible type. By reason of this arrangement it will be seen that as the motor operates the nut 51 will be driven either outwardly or inwardly as determined by the direction of rotation. In moving outwardly it forces the block 25 50 in the same direction, through the medium of spring 53, compressing the spring 18 and causing a closure of the valve 12. In moving in the reverse direction the block 50 is released and accordingly the valve 12 will open under the action 30 of the spring 18 to a degree determined by the governor mechanism. The block 50 carries electrical contact members 58 and 60 engaging suitable conducting and insulating sections as indicated at 62. The switch mechanisms thus provided act to limit the movement of the motor by cutting off the current automatically as the nut 35 51 approaches its limiting positions.

The usual conventional electrical controlling devices for the motor are provided at the location 40 of the gas machine so that the operator may from this remote point control the operation of the blower. These connections are such that an instantaneous operation of the motor in either direction may be effected to cause the turbine to 45 operate at either full or idling speed.

In the operation of the device it will be seen that as the main valve 12 is opened the auxiliary valve 36 is closed and vice versa. Accordingly, either the primary nozzles or the secondary nozzle 50 or nozzles will be effective to drive the turbine at all times, the valve arrangement being such that when the valve 12 is fully closed the valve 36 is 55 fully opened to an extent permitting a full flow of steam through the nozzle 30. In cases of large turbines it will be obvious that the nozzle 30 may be replaced by a plurality of nozzles to maintain the necessary speed to avoid reverse flow of gas.

What I claim and desire to protect by Letters Patent is:

60 1. A turbine including a rotor provided with buckets, primary nozzles for delivering fluid to the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control and means for simultaneously controlling both valve means whereby the primary and secondary nozzles may be rendered alternately effective to drive the rotor.

70 2. A turbine including a rotor provided with buckets, primary nozzles for delivering fluid to

the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control and means for simultaneously controlling both valve means whereby the primary and secondary nozzles may be rendered alternately effective to drive the rotor, said changes of nozzles being effected without stopping of the rotor.

75 3. A turbine including a rotor provided with buckets, primary nozzles for delivering fluid to the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control and means for simultaneously controlling both valve means whereby the primary and secondary nozzles may be rendered alternately effective to drive the rotor, said last means consisting of elements controlled by a reversible motor.

80 4. A turbine including a rotor provided with buckets, primary nozzles for delivering fluid to the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control, and means for simultaneously controlling both valve means whereby the primary and secondary nozzles may be rendered alternately effective to drive the rotor, said last means operating independently of the governing mechanism.

85 5. A turbine including a rotor provided with buckets, primary nozzles for delivering fluid to the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control, and means for simultaneously controlling both valve means whereby the primary and secondary nozzles may be rendered alternately effective to drive the rotor, said governing mechanism being effective to control the first valve means during periods when the primary nozzles are rendered effective by the last named controlling means.

90 6. A turbine including a rotor provided with buckets, primary nozzles for delivering fluid to the buckets to drive the rotor during normal operation, valve means controlling the flow of fluid to the primary nozzles, speed governing mechanism controlling said valve means, at least one secondary nozzle for delivering fluid to the buckets to drive the rotor at idling speeds, valve means controlling flow of fluid to the secondary nozzle, said last named valve means being independent of the governor control, and means for simultaneously controlling both valve means whereby the primary and secondary nozzles may be rendered alternately effective to drive the rotor.
